COMBINED GRADING AND CORONA SHIELD**Robert L. McCoy, Baltimore, Md., assignor to General Electric Company, a corporation of New York****Application March 29, 1955, Serial No. 497,647****9 Claims. (Cl. 174—144)**

This invention relates to a combined grading and corona shield, and more particularly, to a combined grading and corona shield for strain or dead end insulators on high voltage transmission lines to provide flashover protection and improved voltage distribution on the insulator strings and to suppress corona on the articles of line hardware used to connect the transmission conductors to the insulator strings.

In the prior art many forms of combined grading and corona shields are provided which do an adequate job. However, many of these prior art forms of combined grading and corona shields tend to be rather complicated and expensive in that they utilize a comparatively large number of separate pieces in their fabrication. Also, some of these prior art forms of combined grading and corona shields have the disadvantage of not being readily assembled or disassembled with respect to the transmission conductor, line hardware, and insulator string without interference from said last mentioned parts. For instance, the construction of the combined grading and corona shields may be such whereby the transmission conductor can be connected to the insulator string and tensioned only by first connecting the shield with respect to the insulator string and then connecting the transmission conductor to the insulator string. This procedure results in awkward operations in properly tensioning the conductor and may result in damage to the shield or may endanger the safety to the lineman involved in the operation. Likewise, said construction may be such whereby the combined grading and corona shield cannot be removed without breaking the connection between the tensioned transmission line and insulator string.

It is an object of this invention to provide an improved and more economical combined grading and corona shield which will overcome the above discussed disadvantages of the heretofore mentioned prior art forms of combined grading and corona shields.

My invention comprises a combined grading and corona shield having a tube or rod of metal bent into a rectangle with rounded corners having one side thereof open, a pair of tubes or rods of metal each bent into a U-shape with rounded corners, the ends of said pair of tubes or rods connected to said one side and an opposite side of said rectangle, said pair of tubes or rods disposed in generally parallel planes extending generally parallel to the two other sides of said rectangle and generally perpendicular from a same side of the plane of said rectangle, and a strip of metal bent into a U-shape having the legs thereof connected to said pair of tubes or rods adjacent said opposite side and having the base thereof disposed adjacent the center of said rectangle.

The features of my invention which I believe to be novel are set forth with particularity in the appended claims. My invention itself, however, both as to its organization and method of operation, together with further objects and advantages thereof, may best be understood by reference to the following description taken in connection with the accompanying drawing.

2

In the drawing, Fig. 1 is an elevation view of a preferred form of my invention. Fig. 2 is an enlarged perspective view of my preferred form of my invention. Like reference numerals will be used throughout Figs. 1 and 2 to indicate identical parts.

Referring now to the drawing, and more particularly to Fig. 1, my preferred form of invention is illustrated with respect to a transmission line or conductor 1 dead ended to a tower structure 2 by an electrical insulator string 3. As best shown in Fig. 2, the insulator string 3 has two parallel strings of electrical insulators. Each string of the double string 3 comprises inter-connected ball and socket or eye bolt and clevis type electrical insulators which are well known in the art. The transmission line or conductor 1 is connected to the left-hand end of the double insulator string 3 by line hardware comprising a strain clamp 4, a connector 5, a flat yoke plate 6, and a pair of clevis members 7. A jumper loop 8 is electrically connected to the strain clamp 4 and extends downwardly therefrom, and the right-hand end of the double insulator string 3 is connected to the tower structure 2 in a manner well known in the art. In my invention I provide a combined grading and corona shield 9 which can be assembled with respect to the parts 1 and 3—8 without interference therefrom. That is, all the parts shown in Fig. 1 can be inter-connected and tensioned as illustrated, and then the corona shield 9 can be mounted with respect to said parts without any obstruction from said parts. Similarly, the corona shield 9 can be removed with respect to said assembled parts without breaking the tensioned connection therebetween. My combined grading and corona shield 9 will now be described with respect to Fig. 2.

The shield 9 comprises a continuous tubular or rod-like member 10 having a circular cross section or rounded surfaces. Member 10 is bent into a generally flat and rectangular configuration having curved or rounded corners. The opposite ends 11 of member 10 are hemispherical or rounded, and are spaced with respect to each other whereby one side of the rectangular configuration of member 10 is open. Rectangular member 10 is concentrically disposed with respect to the line or axis of the aligned transmission line 1, line hardware 4—7, and double insulator string 3. Member 10 is disposed in generally spaced embracing relationship with respect to the outer or energized ends of the insulators of the double insulator string 3, and is generally disposed in a plane positioned substantially perpendicular to the aforementioned line or axis of the transmission line 1, line hardware 4—7, and double insulator string 3. As will be obvious to those skilled in the art, the purpose of rectangular configured continuous member 10 is to provide flashover protection and improved voltage distribution on the double insulator string 3.

The shield 9 also comprises a pair of identical continuous tubular or rod-like members of metal 12 having a circular cross section or rounded surfaces. Each of the members 12 is bent into a generally U-shape having rounded or curved corners and is connected at its opposite ends to the lower or open side of the rectangular configuration 10 and to the upper or opposite side of the rectangular configuration. As will be obvious to those skilled in the art, in order to minimize sharp projections on the shield 9 the opposite ends of the pair of U-shaped members 12 are preferably connected to the vertically disposed rectangular configured member 10 by smooth welds or the like.

The members 12 are generally disposed within generally parallel planes which extend generally parallel to the two other or left and right-hand sides of member 10 when viewing Fig. 2. Also, the members 12 extend from a same side of the flat plane of member 10 and gen-

erally perpendicular thereto. That is, the members 12 are symmetrically positioned with respect to the axis of the transmission line 1, line hardware 4-7, rectangular configuration 10, and double insulator string 3; and extend from the rectangular member 10 leftwardly along opposite sides of line hardware 4-7 in spaced relationship when viewing Fig. 2. As will be obvious to those skilled in the art, it is a function of the pair of members 12 to suppress corona on the line hardware 4-7.

The members 10 and 12 may be hollow tubular pieces or solid rod-like pieces. However, in order to conserve material, in my invention members 10 and 12 preferably are hollow tubular pieces.

The shield 9 is provided with an attachment fitting for connecting the shield 9 to the flat yoke plate 6 comprising a continuous relatively narrow flat strip of metal 13 bent into a generally U-shaped configuration. The legs of the U-bent strip 13 are connected to the pair of members 12 by smooth welds or the like adjacent to the upper side of the rectangularly bent member 10; and the flat base of the U-bent strip 13 makes flat surface contact with the upper surface of the flat yoke plate 6. Strip 13 is disposed in a plane extending generally parallel to the plane of member 10 whereby the base of strip 13 is disposed adjacent the center of rectangular member 10. A pair of threaded members such as bolts 14 extend through a not shown pair of apertures formed in the base of strip 13 in a direction opposite to that of the legs of strip 13. Preferably, the bolts 14 are permanently connected to the base of strip 13 by welds or the like whereby the number of loose or falling parts of the shield 9 are kept to a minimum. The not shown threaded portions of the bolts 14 extend through a not shown pair of aligned apertures formed in the flat yoke plate 6, and the shield 9 can be removably and securely fastened with respect to the yoke plate 6 by a not shown pair of self-locking nuts threaded on the lower ends of the bolts 14 up against the underside of the flat yoke plate 6.

It is to be noted that the open side of the rectangular member 10 is disposed on the same or bottom side of the aligned parts 1, 4 to 7 and 3 as jumper loop 8. When this is done, jumper loop 8 being at the same potential as member 10, the two parts are mutually shielding; and the presence of member 8 in the proper relationship to the hemispherical ends 11 of member 10 suppresses any corona which would tend to form at ends 11. If the open side of member 10 were located on the upper side of aligned parts 1, 4 to 7, and 3 while jumper loop 8 was still positioned on the bottom side then corona formation would occur at ends 11. Additionally, it is to be noted that the strip 13 is connected to the ends of member 12 disposed adjacent the side of member 10 opposite to the open side of member 10. If the strip 13 were connected to the ends of members 12 opposite from that illustrated in Fig. 2 this would have the effect of closing the open side of the member 10.

It will now be seen that my invention provides a combined grading and corona shield for mounting with respect to a transmission conductor, line hardware, and electrical insulator string without interference or obstruction therefrom. For instance, after the transmission line 1, line hardware 4-7, and double insulator string 3 have been inter-connected and tensioned the shield 9 can be readily mounted with respect thereto by virtue of the open lower side of the rectangularly bent member 10. Final fastening of the corona shield 9 requires only two loose parts such as self-locking nuts for the bolt members 14. Similarly, the corona shield 9 can be readily removed without breaking the connection between the parts 1 and 3-8 merely by removing the pair of self-locking nuts and then lifting the shield 9 away from the transmission line, line hardware, and insulator string assembly by virtue of the open lower side of rectangular member 10.

Additionally, my invention provides a combined grading and corona shield which has a very small number of separate pieces whereby the corona shield is very uncomplicated and economical to manufacture. For one instance, the corona shield comprises only three separate welded pieces 10 and 12. The attachment fitting of the corona shield comprises only three separate welded pieces 13 and 14. The number of loose or falling parts is restricted to two such as the self-locking nuts or the like for the bolts 14.

While there has been shown and described a particular embodiment of the invention, it will be obvious to those skilled in the art that changes and modifications may be made without departing from the invention, and therefore it is intended by the appended claims to cover all such changes and modifications as fall within the true spirit and scope of the invention.

What I claim is new and desire to secure by Letters Patent of the United States is:

- 20 1. A combined grading and corona shield comprising a tubular member having hemispherical closed ends, said tubular member having a generally rectangular configuration open at one of the sides thereof whereby said closed ends are spaced from each other, said rectangular configuration having rounded corners, a pair of tubular members having a generally U-shaped configuration, said U-shaped configuration having a pair of legs joined by a rounded base, said pair of tubular members straddling said one side and the side of said rectangular configuration opposite to said one side and having the opposite ends thereof connected to said one and opposite sides by smooth welds, the planes of said pair of tubular members extending generally parallel to each other and generally perpendicularly from a same side of the plane of said rectangular configuration, said pair of tubular member planes symmetrically disposed with respect to the central axis of said rectangular configuration and generally parallel with respect to the other two sides of said rectangular configuration, and a single piece U-shaped attachment fitting having two leg portions connected by a generally flat base portion, the ends of said leg portions connected to said pair of tubular members adjacent said opposite side by smooth welds, the plane of said attachment fitting extending generally parallel to said rectangular configuration plane and said base portion disposed adjacent said axis, and a pair of threaded members permanently connected to said base portion and extending therefrom in a direction opposite to said leg portions.
- 25 2. A combined grading and corona shield comprising a circular cross sectioned continuous rod-like member having rounded ends, said rod-like member bent into a generally rectangular configuration having curved corners, said rounded ends spaced from each other whereby one side of said rectangular configuration is open, a pair of circular cross sectioned continuous rod-like members each bent into a generally U-shaped configuration having a pair of legs joined by a rounded base, opposite ends of said pair of members connected to said one side and a side of said rectangular configuration opposite to said one side, the planes of said pair of members extending generally parallel to the other sides of said rectangular configuration and generally perpendicular from a same side of the plane of said rectangular configuration, and a single piece generally U-shaped attachment fitting having the legs thereof connected to the legs of said pair of members adjacent said opposite side and the base thereof disposed adjacent the center of said rectangular configuration, the plane of said attachment fitting extending generally parallel to the plane of said rectangular configuration.
- 30 3. A combined grading and corona shield comprising a continuous rod-like member having rounded ends bent into a rectangular configuration having rounded corners, said rounded ends spaced from each other whereby one

side of said rectangular configuration is open, a pair of continuous rod-like members each bent into a curved U-shaped configuration, the ends of said pair of members connected to said one side and a side of said rectangular configuration opposite thereto, said pair of members extending from a same side of the plane of said rectangular configuration and disposed in parallel planes extending perpendicular to said rectangular configuration plane and parallel to the other sides of said rectangular configuration, and a U-shaped attachment fitting having the legs thereof connected to said pair of members adjacent said opposite side and having the base thereof disposed adjacent the center of said rectangular configuration.

4. A four piece combined grading and corona shield comprising an elongated and rounded continuous metallic member bent into a rectangle having rounded corners, opposite ends of said member spaced from each other whereby one side of said rectangle is open, a pair of elongated and rounded continuous metallic members each bent into a U-shape having rounded corners, the ends of said pair of members connected to said one side and an opposite side of said rectangle, said pair of members positioned in parallel planes disposed parallel to the other two sides of said rectangle and extending perpendicularly from a same side of the plane of said rectangle, and a continuous strip of metal bent into a U-shape having the legs thereof connected to said pair of members adjacent said opposite side and the base thereof disposed adjacent the center of said rectangle.

5. A unitary combined grading and corona shield having only six different parts comprising an elongated and rounded continuous metallic member bent into a rectangle having rounded corners, opposite ends of said member spaced from each other whereby one side of said rectangle is open, a pair of elongated and rounded continuous metallic members each bent into a U-shape having rounded corners, the ends of said pair of members connected to said one side and an opposite side of said rectangle, said pair of members positioned in parallel planes disposed parallel to the other two sides of said rectangle and extending perpendicularly from a same side of the plane of said rectangle, and a continuous strip of metal bent into a U-shape having the legs thereof connected to said pair of members adjacent said opposite side and having the base thereof disposed adjacent the center of said rectangle, the plane of said another strip disposed parallel to the plane of said rectangle, and a pair of threaded members connected to said base and extending in a direction opposite to said legs.

6. A combined grading and corona shield comprising an elongated metallic member bent into a rectangle having one side thereof open, a pair of elongated metallic members each bent into a U-shape, the ends of said pair of members connected to said one side and an opposite side of said rectangle, said pair of members disposed in generally parallel planes extending generally parallel to the two other sides of said rectangle and generally perpendicular from a same side of the plane of said rectangle, another elongated metallic member bent into a U-shape having the legs thereof connected to said pair of members adjacent said opposite side and having the base thereof disposed adjacent the center of said rectangle.

7. A combined grading and corona shield comprising a rounded tubular elongated metallic member bent into a rectangle having one side thereof open, a pair of rounded tubular elongated metallic members each bent into a U-shape, the ends of said pair of members con-

nected to said one side and an opposite side of said rectangle, said pair of members disposed in generally parallel planes extending generally parallel to the two other sides of said rectangle and generally perpendicular from a same side of the plane of said rectangle, and a strip of metal bent into a U-shape having the legs thereof connected to said pair of members adjacent said opposite side and having the base thereof disposed adjacent the center of said rectangle, said strip disposed in a plane generally parallel to said rectangle plane, and a pair of attachment members connected to said base and extending therefrom in a direction opposite to said legs.

8. In a generally horizontally disposed electrical transmission conductor connected at one end thereof by metallic connecting means to one end of a generally horizontally disposed electrical insulator string, means for grading the voltage distribution along said insulator string and suppressing corona at said connecting means comprising a rounded elongated metallic member bent into a rectangle open at one side thereof, said rectangle generally surrounding said insulator string one end and generally disposed in a vertical plane, a pair of rounded elongated metallic members each bent into a U-shape and connected at the ends thereof to said one side and an opposite side of said rectangle, said pair of members positioned in generally parallel planes disposed generally parallel to the other two sides of said rectangle and extending generally perpendicularly from a same side of the plane of said rectangle along opposite sides of said connecting means, an elongated strip of metal bent into a U-shape having the legs thereof connected to said pair of members adjacent said opposite side and having the base thereof disposed adjacent the center of said rectangle, and means removably attaching said base to said connecting means.

9. In an elongated electrical conductor connected at one end thereof by a metallic yoke plate to one end of a double electrical insulator string, said conductor and string disposed along an identical generally horizontal line and a jumper loop depending from a bottom side of said conductor, a combined voltage grading and corona suppressing shield comprising a continuous rounded tubular member bent into a flat rectangle, the opposite ends of said tubular member being rounded and spaced from each other whereby one side of said rectangle is open, a pair of continuous rounded tubular members each bent into a flat U-shape and having the opposite ends thereof connected to said one side and an opposite side of said rectangle, said rectangle and U-shape having rounded corners, said rectangle concentrically disposed about said string one end and said pair of tubular members positioned in parallel planes disposed parallel to the other two sides of said rectangle and extending perpendicularly from a same side of the plane of said rectangle along opposite sides of said yoke plate and line, said one side disposed adjacent said conductor bottom side, and a flat continuous strip of metal bent into a U-shape having the legs thereof connected to said pair of members adjacent said opposite side and having the base thereof disposed adjacent the center of said rectangle, said base making flat surface engagement with said yoke plate and means removably attaching said base to said yoke plate.
